(57) **CLAIM**

The ornamental design for the "chaise", as shown and described.

DESCRIPTION

FIG. 1 is a front elevational view of a chaise showing my design.

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a perspective view thereof.

The fragmented cross-hatching shown on the top and bottom of the chaise in FIGS. 2, 3, 4, 6 and 7 is understood to represent fabric and would be continuous throughout the circumscribed area. The fragmented depiction of a weave pattern, shown in FIGS. 1, 2, 5, 6 and 7, is understood to repeat uniformly throughout the circumscribed areas.
